J. A. BARKER,
PAINTER'S GUARD.
APPLICATION FILED FEB. 5, 1918.

1,287,181.

Patented Dec. 10, 1918.

Fig. 1.

UNITED STATES PATENT OFFICE.

JOHN A. BARKER, OF RICHMOND, VIRGINIA.

PAINTER'S GUARD.

1,287,181.

Specification of Letters Patent. Patented Dec. 10, 1918.

Application filed February 5, 1918. Serial No. 215,524.

To all whom it may concern:

Be it known that I, JOHN A. BARKER, a citizen of the United States, residing at Richmond, in the county of Henrico and State of Virginia, have invented certain new and useful Improvements in Painters' Guards, of which the following is a specification.

This invention relates to guards for painters' use.

The object is to provide a device which may be readily held in proper position by one hand of an operator to effectually cover up a portion of a surface, while the other hand is employed in manipulating a brush to apply paint, varnish or other similar coating to that surface or portion thereof desired to be painted.

Another object is to construct the device so that the same may be equally well adapted for use, as above stated, either upon a flat surface, as for instance in blocking out to imitate tile work and other decorative work, or for use in angles between surfaces such as between a window pane and sash, where the former must be covered while the adjacent faces of the sash are being painted.

A further object is to provide a device of this character which may be cheaply manufactured of sheet metal by stamping out a suitable blank therefrom and bending the parts and securing them into form as by soldering the same, and providing means for preventing dripping or splashing of any excess paint or other coating over the back or sides of the device during the operation of applying said paint or coating.

A full and complete understanding of the invention may be obtained from a consideration of the following detailed description, taken in connection with the accompanying drawing forming a part of this specification; it being understood that while the drawing shows a practical form of the invention, the latter is not confined to strict conformity therewith, but may be changed or modified, so long as such changes or modifications mark no material departure from the salient features of the invention, as specifically pointed out in the claims appended hereto.

In the drawing, in which like reference characters designate corresponding parts in each of the several figures:—

Figure 1 is a face view of the device in position for use in painting the edges of

a window sash, the full and dotted lines indicating the different positions assumed by the guard.

Fig. 2 is an inverted plan view of the device.

Fig. 3 is a longitudinal sectional view thereof.

Fig. 4 is a perspective view of the device on a somewhat enlarged scale.

Fig. 5 is a plan view of the blank from which the device is formed.

The present invention consists primarily in a scoop-like body member formed from a suitable blank stamped from sheet metal of the proper gage and stiffness. This blank, as illustrated in Fig. 5 of the drawing, consists of an elongated bottom portion 1 having oppositely disposed side members 2 and 3 integrally connected therewith along its long sides and adapted to be bent upwardly, at right angles thereto, to form perpendicularly disposed side walls 2, 3 for a purpose to be explained.

The bottom portion 1, or wall, of the blank is wider at what may be termed the front or open end thereof than at the back or closed end, the metal composing the blank being bent along the lines indicated at 4 and 5, in Fig. 5, so that the side members 2 and 3 may assume the position illustrated in the other figures of the drawing.

The blank is further provided, at its narrow end with a back wall or portion 6 of equal width therewith, and adapted to be bent into an upstanding position along the line indicated at 7, in a like manner to the side members 2 and 3, the top edge of said back wall 6, when so bent, being flush with the top edges of the side members or walls.

Tabs or extensions 8 and 9 are formed integrally with the side edges of the back wall 6, and are adapted to be bent at nearly right angles thereto, along the lines indicated at 10 and 11, so that, when the said back wall is in position perpendicular to the bottom 1, the tabs or extensions 8 and 9 will lie along the outside of the adjacent ends of the side members or walls 2 and 3, to which they may be suitably secured as by soldering, thus forming when set up in the manner described, an open-ended receptacle composed of a bottom, rearwardly converging side walls and a back wall, as clearly illustrated in Fig. 4 of the drawing.

The blank is still further provided with an integral extension 12, projecting from

that edge of the back wall 6 which constitutes the top edge thereof when the same is bent into position and at the center thereof, and having its transversely disposed 5 terminal portions 13 and 14 severed from the back member, as indicated at 15 and 16, and free to be bent into tubular shape to form a socket 17, the axis of which is arranged substantially at right-angles to the 10 back wall or member 6, longitudinally of the body of the guard and midway of the width thereof.

A handle 18, preferably formed of wood, is fitted into the socket 17 and retained 15 therein by a screw 19 passing through the wall of the socket and entering the said handle.

A heel member 20, composed of an angularly bent piece of metal, is soldered or 20 otherwise secured to the underside of the bottom member 1, at the rear or narrow end thereof and directly beneath the back wall 6, the same being so arranged as to support the completed guard in an inclined position 25 with one of the thin edges of the angularly bent heel member 20 resting upon the supporting surface, as clearly shown in Fig. 3 of the drawing.

By reason of the inclination of the bottom member 1, caused by the heel member 20, when the device is resting upon a surface, the front edges of the side members 2 and 3 at the open end of the device, are cut back, as indicated at 2^a and 3^a (Fig. 5), in 35 order that the said edges may extend vertically to fit squarely against a surface at right angles to the base, as shown in Fig. 3.

The length of the heel member is exactly the same as the width of the open front end 40 of the guard, and it is secured to the narrow rear end of the guard with its terminal portions extending equal distances beyond either side thereof, so as to assist in the proper positioning of the device within the 45 corner of a window sash or similar place, in the manner illustrated in Fig. 1 of the drawing.

When it is desired to use the device while 50 painting, say, the wash-board around the base of the walls of a room, it is only necessary to place the guard in the position shown in Fig. 3 of the drawing, with the open top of the guard uppermost, the open wide end of the same next to the wash-board 21 with 55 the relatively thin edge of the bottom 1 located directly in the angle of said wash-board and the floor 22, and the relatively thin portion of the heel member 20 resting upon said floor. The paint brush may then 60 be applied to the wash-board with freedom and with the assurance that no paint will reach the floor 22 by reason of the bottom 1 and the side walls 2 and 3 which prevent any splashing. The brush is operated be- 65 tween the side walls to apply paint to the

surface defined by the ends of the side walls at the open end of the device.

When it is desired to use the device while painting the edges of a window sash or in any similar use, as illustrated in Fig. 1, it 70 will be seen that the device is placed with the heel member 20 resting against the glass 23, the front edge of the base member 1 at the open end thereof being arranged in the angle between the said glass and the side 75 rail of the sash 24, when, in the same manner as heretofore described, the process of coating the desired parts may be proceeded with without the danger of spattering or accidentally passing the brush over parts not 80 to be coated. In the latter use of the device it will also be seen that the side walls 85 2 and 3 will catch any drippings from the brush during the process of painting the vertical side rails of the window sash. The dotted line position of the guard in Fig. 1 of the drawing shows the manner of using the same while painting the bottom rail of the window sash.

In some instances where it may be found 90 advantageous, the guard and the brush may be moved together, transversely with relation to the guard, so as to cause the active end of the brush to traverse the proper path in order to coat the desired surface. In this event the open end of the guard is held 95 in engagement with the angle formed between two surfaces and is moved along laterally, the heel member acting as a runner to permit an easy sliding movement and permit the brush to properly function, and it will be seen that the guard is capable of being manipulated together with the brush by one hand of the operator in this manner.

The full and dotted line positions of the 105 device, as illustrated in Fig. 1, are indicative thereof when used in painting the left hand side and bottom rails of a sash; and it will be understood that by reversing or inverting the device the same may be used on 110 the opposite side rails or the top rail of said sash.

The guard or fender may be made in any 115 desired size and proportion, the smaller sizes being adapted for narrow line and border work, etc., while some other size will be found better adapted for painting or cal- 120 cimining larger surfaces as where a ceiling is to be coated with one color and the side walls with another.

In blocking out work, such as in the representation of tiles, the device will be placed upon the surface, outside of the block to be coated, and in the same position shown in Fig. 3. After carefully outlining the border 125 of the block in this manner, the center thereof may be easily and quickly filled in, without the use of the device, by a separate and larger brush if desired, and it will thus be seen that the invention may be used in work 130

of high quality and will result in more rapid execution of the same.

From the foregoing the merits of the invention will be appreciated, and it will be seen that a simple, cheap and durable device has been provided as a guard to be used by painters which will greatly facilitate their work and prevent spoiling adjacent surfaces when painting.

10 What I claim is:—

1. A paint guard comprising a member having a bottom wall and opposite side walls arising therefrom and extending throughout the length of said bottom wall, the front edges of the said walls sloping rearwardly with relation to the bottom, said walls defining a paint brush receiving space, and forming three guarding walls for said brush to protect adjacent surfaces when painting, and means for raising the bottom wall to cause the front edges of the said walls to assume a vertical position when the device is resting upon a support.

2. A paint guard comprising a member having a bottom, a handle, and opposite side walls extending upwardly from the bottom and converging toward one end, whereby the member is less in width at one end than the other, said side walls and bottom wall constituting three guarding walls between the paint brush and the surface to be protected, and means projecting from the member at the smaller end and equally from each side thereof, so as to support either side wall in rear of the larger end away from the surface to be protected.

3. A paint guard comprising a member having a bottom, an end wall, a handle, and opposite side walls arising from the bottom and extending forwardly from the end wall, the space between the side walls at the other end being open, said side walls terminating at the open end of the member, whereby the ends of the side walls and bottom at said open end are caused to bear against the surface being painted, and means for elevating the bottom above the protected surface except at the open end of the member.

4. A paint guard comprising a member having a bottom, one end wall, a handle, and opposite side walls extending upwardly from the bottom and forwardly from the end wall, the space between the side walls at the other end being open, and a heel provided on the bottom at the closed end of the member to elevate the main portion of the bottom from the surface being protected.

5. A paint guard comprising a member having a bottom wall, an end wall and op-

posite side walls, the other end being open, said member tapering toward the closed end, and means projecting from said member at the closed end equally from each side thereof so as to support either side wall in rear of the open end above the surface to be protected.

6. A paint guard comprising a member having a bottom wall, an end wall and opposite side walls, the other end being open, said member tapering toward the closed end, and a heel provided on the bottom wall at said closed end, said heel being equal in length to the widest portion of said member.

7. A paint guard comprising a bottom plate having its side edges converging from front to back, perpendicular side walls rising from the said edges, a back wall connected to the narrow end of the bottom plate and joined to the back ends of the side walls and of even height therewith, a heel member secured transversely to the underside of the bottom member at the narrow end thereof, and a handle connected to said back wall.

8. A paint guard comprising a bottom plate with rearwardly tapering side edges and parallel front and rear edges, perpendicular walls rising from the side and rear edges thereof and joined at their meeting edges, the front ends of the side walls sloping rearwardly with relation to the bottom, a transversely disposed heel member carried by the bottom plate and adapted to raise the back end thereof and cause the said sloping front edges of the side walls to assume a vertical position when the device is resting upon a support, and a handle connected to the back wall.

9. A paint guard comprising a bottom plate having rearwardly tapered side edges provided with substantially perpendicular walls, a back wall joined to the rear narrow end of the bottom plate and also to the adjacent edges of the side walls, a rearwardly extending handle socket carried by the back wall, and an angular heel member secured transversely to the under side of the bottom member at the narrower end thereof, said heel member being of a length equal to the width of the front end of the bottom and extending equally from each side thereof.

In testimony whereof I affix my signature in the presence of two witnesses.

JOHN A. BARKER.
